[57] ABSTRACT

A detachable absorbent liner for the sweat band of a hard hat is of one-piece form including extension foldable over the edges of the sweat band; the extensions are faced with opposable pressure-actuable material.

SWEAT BAND FOR A HARD HAT SUSPENSION UNIT

This invention relates to a hard hat, and in particular to a removable liner as a comfort aid to the wearer.

The usual hard hat has an adjustable band to enable the hat to be comfortably fitted. This band is non-absorbent, usually of plastic. In the winter the band becomes cold, resulting in a feeling of discomfort where it contacts the forehead. In the summer, the same part in contact with the forehead becomes slippery because of perspiration.

The band is suspended inside the hat by a harness attached to a center crown pad which rests on the top of the head. This pad is also of non-absorbent plastic, having the same discomfort characteristics.

The object of the present invention is to alleviate such discomfort and specifically to accomplish this by means of a liner of absorbent material configured to fit the band, the liner having opposable tabs faced with pressure — sensitive adhering material enabling the liner to be easily detached and rolled up to fit a pocket. This arrangement may be used also to line the crown pad.

IN THE DRAWING

FIG. 1 is a perspective view of a hard hat suspension equipped in accordance with the present invention;

FIG. 2 is a perspective view of the band liner of the present invention;

FIG. 3 is a sectional view on the line 3—3 of FIG. 2;

FIG. 4 is a sectional view similar to FIG. 3, showing a modified form of head band liner; and

FIG. 5 is a perspective view of a crown pad liner.

The structure identified by reference character 10 in FIG. 1 is a head cradle or suspension positionable inside a hard hat. The suspension 10 comprises a plastic band 11, adjustable in nature to comfortably encircle the head. A plurality of integral spikes 12 extend upwardly from the upper edge of the band 11 and these serve to anchor a harness comprising a plurality of adjustable straps 13 which support a crown pad 14 resting on the top of the wearer's head.

The normal head band 11 and the crown pad as well are non-absorbent and result in considerable discomfort in hot weather and cold weather as well. Thus the non-porous plastic or other synthetic material of which the band 11 and pad 14 are composed do not absorb perspiration nor is the material a good heat conductor.

Under and in accordance with the present invention discomfort to the wearer is alleviated by affording an absorbent liner strip 20 adapted to be removably attached to the band 11 at least in the portion which girdles the brow of the wearer, approximately 180° from one temple to the other. The liner 20 can be easily detached and rolled to fit a pocket when not in use, as at the end of the day's work, or discarded or washed for re-use.

Details of the liner are shown in FIGS. 2 and 3. The liner is composed of an absorbent cloth material or wet-strength cellulosics, preferably folded and reverse folded at F1 and F2 so as to present along one edge a one-ply flap 22 and an opposed one-ply flap 23. The folds are secured by stitches S1 and S2.

The flap 23 in its original entirety is identified by phantom line in FIG. 2, because a great deal of the material in rectangular patches is subsequently slit and re-

moved, thereby to afford a plurality of rectangular tabs 24 at what constitutes one edge of the liner 20.

The other flap 22 is slit at intervals, slits SL. Resultantly, there are a plurality of flap extensions, 25, 26, 27, 28 and 29 in spaced relation along the corresponding edge of the liner 20.

The extensions as 25-29 are provided with pressure actuatable adhering elements 30, FIG. 3. The adhering elements may be hooked fabric such as the VELTROL brand or they may be a pressure actuatable adhesive, easily separated when pressed against like material as in the instance of the VELTROL type pressure actuatable fastener.

In like manner, the opposable tabs 24, opposable to the extensions as 25 as hereinafter described, are faced at the free ends thereof with pressure actuatable fastener elements 31. There are at least two tabs 24 for each of the end extensions 25 and 29 and in this connection it will be observed in FIG. 3 that the fastener elements 30 are on one side of the extensions as 25 while the opposable fastener elements 31 on the tabs 24 are on the opposite side.

The extensions 25 — 29 are to be folded upwardly around the lower edge of the band 11; the tabs 24 are folded down, FIG. 1, and the adhering elements are engaged on the outside of the band 11. In use the band 20 representing a multiple ply absorbent liner to bear against the wearer's brow or forehead is positioned on the inside of the head band 11 as shown in FIG. 1 with the medial extension 27 located between and below the two spikes 12-1 and 12-2 which identify the forehead portion of the band 11. The extensions as 25 are then folded up over the lower edge of the band 11, and the opposable tabs 24 are then folded downwardly to bring the adhering elements 30 and 31 into mating relation, pressing the two together.

It is sufficient to afford two tabs 24 to anchor the end extensions 25 and 29; one tab 24 suffices for the others. The slits SL enable the liner to conform to both the band 11 and the forehead; the liner will not roll or slip around the head.

The invention may be embodied as well in an unfolded, single ply absorbent liner 35, FIG. 4, which is otherwise identical in configuration to the liner 20.

Especially for winter wear, and to ease the harness contact a protective liner 40, FIG. 5, of like absorbent material may be located at the underside of the crown pad, the liner 40 having two attaching tabs 42 provided at the free ends with opposable pressure actuatable fastener elements 43 matable at the top of the pad as shown in FIG. 5.

The present invention, at little cost, affords more comfort to the person wearing a hard hat; the liner is easily applied and just as easily detached, and can be folded when not in use, washed or even discarded.

I claim:

1. In a hard hat having a non-absorbent band with opposed edges which encompasses the head of the wearer and in which the band has spaced upright spikes which anchor a suspension harness comprising straps attached to a center crown pad; a liner of absorbent material comprising a strip lining the inside of the band and of a length to span the forehead of the wearer, said strip having on one edge a plurality of spaced elongated extensions foldable over one edge of the band, said strip having on the other edge a plurality of tabs foldable over the other edge of the band to meet the

folded extensions, and said extensions and said tabs having opposable pressure actuatable adhering elements at the free ends thereof selected from the group consisting of pressure actuatable adhesive and pressure actuatable hooked fabric.

2. The liner of claim 1 in which the end extensions on the strip each present two spaced adhering elements and in which there are two tabs for each such end extension.

3. The liner of claim 2 in which the strip is one ply.

4. The liner of claim 2 in which the strip is folded to present multiple plies.

5. A hard hat having an internal suspender including a non-absorbent band having opposed upper and lower edges which encompasses the head of the wearer and in which the band has spaced upright spikes which anchor a suspension harness comprising straps attached to a center, crown pad; a first liner of absorbent material comprising a strip lining the inside of the band and of a length to span the forehead of the wearer, said strip

having on one edge a plurality of spaced elongated extensions foldable over one edge of the band, said strip having on the opposed edge a plurality of tabs foldable over the other edge of the band to meet the folded extensions, said extensions and said tabs having opposable pressure actuatable adhering elements at the free ends thereof selected from the group consisting of pressure actuatable adhesive and pressure actuatable hooked fabric, and a second liner of absorbent material located on the underside of the crown pad and having at least two tabs faced with pressure actuatable fasteners joined one to another at the top of the pad.

6. The hat of claim 5 in which the end-most extensions on the strip each present two spaced adhering elements.

7. The liner of claim 6 in which the strip is one ply.

8. The liner of claim 6 in which the strip is folded to present multiple plies.
